(57) **CLAIM**

The ornamental design for an arcade game machine, as shown and described.

DESCRIPTION

FIG. 1 is an isometric view of an arcade game machine showing my new design;

FIG. 2 is a side elevational view thereof;

FIG. 3 is a top plan view thereof;

FIG. 4 is a rear plan view thereof; and,

FIG. 5 is a front elevational view thereof showing my design. The elements shown in broken lines are for the purpose of illustrating and form no part of the claimed design.

1 Claim, 5 Drawing Sheets
